UNITED STATES PATENT OFFICE

169,413

CARVING KNIFE OR THE LIKE

Sam H. Bordelon, Chicago, Ill., assignor to Arthur Salm Inc., Chicago, Ill., a corporation of Illinois

Application December 26, 1952, Serial No. 22,884

Term of patent 14 years

(Cl. D22—3)

To all whom it may concern:

Be it known that I, Sam H. Bordelon, a citizen of the United States, residing at Chicago, in the county of Cook and State of Illinois, have invented a new, original, and ornamental Design for a Carving Knife or the like, of which the following is a specification, reference being had to the accompanying drawing, forming part thereof.

In the drawing

I claim:

The ornamental design for a carving knife or the like, as shown.

SAM H. BORDELON.
